(57) **CLAIM**

The ornamental design for a channel fastener, as shown and described.

DESCRIPTION

FIG. 1 is an upper isometric view of a channel fastener in a locked configuration showing the new design;
FIG. 2 is a lower isometric view thereof;
FIG. 3 is a front view thereof;
FIG. 4 is a rear view thereof;
FIG. 5 is a left side view thereof;
FIG. 6 is a right side view thereof;
FIG. 7 is a top view thereof;
FIG. 8 is a bottom view thereof;
FIG. 9 is an upper isometric view of the channel fastener in an unlocked configuration;
FIG. 10 is a lower isometric view thereof;
FIG. 11 is a front view thereof;
FIG. 12 is a rear view thereof;
FIG. 13 is a left side view thereof;
FIG. 14 is a right side view thereof;
FIG. 15 is a top view thereof;
FIG. 16 is a bottom view thereof;
FIG. 17 is an upper isometric view of the channel fastener in a transitioning configuration;
FIG. 18 is a lower isometric view thereof;
FIG. 19 is a front view thereof;
FIG. 20 is a rear view thereof;
FIG. 21 is a left side view thereof;
FIG. 22 is a right side view thereof;
FIG. 23 is a top view thereof; and,
FIG. 24 is a bottom view thereof.
